WRIST WATCH BRACELET

Theodore Lundman, Hopkins, Minn.

Application February 9, 1938, Serial No. 189,604

1 Claim. (Cl. 24—71)

My invention relates to a bracelet especially adapted for holding wrist watches and which is of the safety type, that is, one that is circumferentially expansible and contractible. Generally stated, the invention consists of the novel devices, combination of devices and arrangement of parts hereinafter described and defined in the claim.

In the accompanying drawing which illustrates the invention, like characters indicate like parts throughout the several views:

Referring to the drawing:

Fig. 1 is a perspective showing the human hand by dotted lines, and showing two wrist watches and bracelets, one applied to the wrist of the hand, and the other expanded for application to the hand;

Fig. 2 is a plan view showing the device on an enlarged scale, some parts being broken away;

Fig. 3 is a section taken on the line 3—3 of Fig. 2;

Fig. 4 is a section taken on the line 4—4 of Fig. 2; and

Fig. 5 is a section taken on the same line as Fig. 2, but on a smaller scale and showing the coupling elements of the bracelet extended.

The wrist watch, as shown, is indicated as an entirety by the character 6. To lugs on the ends of the wrist watch casing are attached flexible main sections, shown as made up of link chains 7 and 8. The chain 8 is attached to one end of an inverted metal channel or segmental coupling hood 9 that has sliding engagement with channels formed by flanges 10 of a correspondingly curved segmental coupling segment 11.

As best shown in Fig. 3, the coupling segment 9 has outturned flanges 12 that slide in the channels formed by the flanges 10 of segmental coupling segment 11. The extending or expanding sliding movement of the segments 9 and 11 is limited by engagement of stop lugs 13 and 14 respectively on the segments 9 and 11. A pair of reversely curved, preferably flat sheet extension links 15 and 16 are hingedly connected at 17. The link 15 is pivotally connected at 18, to a lug on the extended end of the coupling segment 11; while the extended end of the link 16 is pivoted to the extended link of the chain 7. A leaf-like latch spring 19 is connected at one end to the convex surface of the link 16, with its free end sprung away from said link, as approximately shown in Figs. 4 and 5. The latch spring 19 is formed with notches or perforations 20 that are adapted to be engaged by inturned lock detent lug

21, formed on the extended end of the coupling segment 9.

When the bracelet is extended, as shown in Fig. 4, and at the left in Fig. 1, the bracelet may be freely slipped over the hand, either onto or off from the wrist, but the bracelet will remain as a complete band that will not accidentally fall off from the hand. When the bracelet is to be contracted on to the wrist, the link 15 is turned over into the channel of the joint segment 11, 10 and the link 16 is pressed down on to the link 15; and then the links 15 and 16, thus forced together, are slid into the hood or under the top plate of the coupling segment 9. The extent to which the bracelet will be contracted may be varied by setting one or the other of the perforations or notches 20 in engagement with the lock detent lug 21 of the coupling segment 9. Fig. 4 clearly illustrates the latter noted adjustment, to wit: an adjustment corresponding to that shown to the right in Fig. 1, and also in Fig. 2. In all of the adjustments of the bracelet to the wrist, the folded links 15 and 16, and the main body of the spring latch 19, are covered by the hood of the coupling segment 9, with only the extreme end 25 of the latch 19 exposed.

It is important to note that when the bracelet is contracted onto the wrist, the leaf-like links 15 and 16, which are then folded together and against the bottom of the coupling segment 11, 30 are forced into the segmental space formed between the overlying hood 9 and the said base forming lower segment 11, and hence, cannot possibly unfold to permit opening expansion of the bracelet. Before the unfolding and expanding 35 movement can be produced the folded links 15 and 16 must be drawn out of the hood and then, of course, they can be folded or extended, as shown in Fig. 5.

To release and unlock the bracelet for opening 40 movement, or for readjustment, it is only necessary to slightly press downward on the exposed end of the latch spring 19.

By reference to the drawing, it will be seen that the coupling segment 11, on its convex surface, is channel shaped and affords a guide and keeper for the segment 9; and that the segment 9 is of inverted channel shape form and affords a segmental hood to cover the curved links 15 and 16.

This improved bracelet has been made and found efficient for the purposes had in view.

What I claim is:

In a device of the kind described, a lower coupling segment having upwardly and inwardly

turned marginal guide channel-forming flanges, an upwardly bulged upper hood-forming segment having downwardly and outwardly turned marginal flanges slidable in the channels formed by the inturned flanges of said lower coupling segment, the said hood-forming upper segment being normally open at its bottom, said lower segment affording the bottom to said hood-forming segment when slid within the same, a link hingedly connected to the extended end of said lower coupling segment, a second link pivoted to the free

end of said first noted link, a flexible connection between the extended end of said second noted link and the extended end of said upper coupling segment, said two links being foldable together and into the channel of said lower coupling segment and then adapted to be slid under the hood-forming portion of said upper coupling segment, and means for securing said two coupling segments in different adjustments with the links folded as stated. 5 10

THEODORE LUNDMAN.
